RAY E. BURNS, OF SYRACUSE, NEW YORK.

NON-REFILLABLE BOTTLE.

1,272,376.

Specification of Letters Patent. Patented July 16, 1918.

Application filed March 20, 1917. Serial No. 156,026.

To all whom it may concern:

Be it known that I, RAY E. BURNS, a citizen of the United States, residing at Syracuse, in the county of Onondaga and State 5 of New York, have invented certain new and useful Improvements in Non-Refillable Bottles, of which the following is a specification.

This invention relates to improvements in 10 non-refillable bottles, and has for its object to generally improve and simplify the construction and operation of devices of this class.

The various features and parts of the invention will be understood from the detailed description which follows and by reference 15 to the accompanying drawing, in which—

Figure 1 is a central vertical section showing my improvement applied thereto, in 20 which the valve is in the position for preventing refilling of the bottle.

Fig. 2 is a similar sectional view in which the valve is released for allowing the contents of the bottle to be drawn out.

Figs. 3 and 4 are respectively a top plan 25 view and a side elevation of the threaded stopper.

Figs. 5 and 6 are respectively top plan view and side elevation of the valve shown 30 in Figs. 1 and 2.

In the drawing, 2 represents the body of a bottle or like liquid container, and 3 is the neck having a bore 4. 5 represents an internal threaded portion intermediate the 35 ends of the neck, and 6 represents a reduced opening or port arranged in a flange 7 at the base of the neck. In the preferred form, the bore of the neck between the threaded portion 5 and the flange 7 is tapered, as 40 shown in Figs. 1 and 2. In filling as well as emptying the bottle 2 the liquid must pass through the port 6, and at the time of the filling the neck is preferably free and clear of any obstructions. After the liquid is forced into, or otherwise applied to the bottle 2, a valve X preferably tapered, corresponding to the shape of the lower portion 45 of the neck, is placed in position upon the flange 7, as shown in Fig. 1, in which position the valve completely closes the port 6. The next step consists of screwing into the threaded portion 4 a threaded stopper 8, which has an opening 9 through its center in line with the port 6. In order to apply 50 the stopper 8, the top surface thereof is provided with radial angular notches 10 to re-

ceive a screw driver or like instrument. The notches 10 in the drawing are formed with one straight vertical edge or shoulder 10'. The opposite sides of the said notches comprise inclined surfaces 10'' (in the drawing, the notches 10 are arranged for right hand screw threads). By this construction and arrangement, the stopper may only be driven into the threaded portion of the neck by the right hand turning of a screw driver, 60 and the purpose of the peculiar notches 10 is to prevent the stopper 8 from being unscrewed or removed after it is once driven tightly into the threaded portion of the neck. After the stopper is applied as described, 65 a common cork 11 may be forced into the clear top portion of the neck, as shown by dotted lines in Fig. 1. To draw off the liquid, the cork 11 is first removed, the bottle should then be tilted as shown, in Fig. 2. 70 The liquid flowing through the port 6 then forces the valve X away from the seat 7 toward and against the bottom side of the stopper 8, and as the bore of the neck increases in diameter toward the stopper, a 75 considerable space is provided around the valve to allow the liquid to flow uninterruptedly. The top of the valve X is preferably flat corresponding to the bottom of the stopper 8 and to allow the liquid to reach the port 9 of the stopper, I provide a number of V-shaped radial grooves or notches 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 valves X are also novel and durable and provide adequate security against the refilling of the bottles after the original liquids are once drawn off.

5 Having thus described my invention, what I claim as new and desire to secure by Letters Patent, is—

In a non-refillable bottle, the combination of a hollow neck separated interiorly from 10 the body of the bottle by an annular flange forming a central port, the interior of the neck provided intermediate its ends with screw threads, the portion of the neck be-

tween said threads and the free end thereof being cylindrical and adapted to receive a 15 cork, the interior of the neck below said threads gradually tapering and contracting to said flange, a threaded stopper having a central liquid port irremovably disposed in the threaded portion of the neck; and a 20 gravitational float-valve disposed in the contracted interior adapted to control the flow of the liquid through the port in said flange.

In testimony whereof I affix my signature.

RAY E. BURNS.
